UNITED STATES PATENT OFFICE

GEORGES MARCONNET, OF PARIS, FRANCE

PROPELLION OF SHIPS

Application filed December 2, 1930, Serial No. 499,585, and in France December 6, 1929.

The present invention relates to the propulsion of ships, and aims at reducing the resistance offered to their progress by the friction of the hull in the water.

To this effect, the invention consists of blowing a great number of air bubbles into the water along the sides of the hull, more particularly at the front of the ship. These air bubbles are meant to form a kind of emulsion with the water which has a lower friction coefficient than water.

In order to put this procedure into practice, one can, for example, build the front part of the ship on a length of several yards and as far as it is under water, with a double hull. The space between the two walls is supplied with compressed air under suitable pressure, and the outer wall is perforated by a great number of small holes which give escape to air bubbles without interruption while the ship moves.

Since the latter advances, while the bubbles rise to the surface, the bubbles will slide along the oblique outlines of the hull's surface, and thus they will form a coat of emulsion starting at the bows, which will cover a great part of the surface of the hull.

If necessary, other perforated walls can be arranged on the sides of the ship; for instance near the middle of its length, so as to extend as much as possible the advantage of the reduced friction in the water.

Calculations show that a slight reduction of the coefficient of friction is sufficient to obtain a marked reduction in the fuel consumption, the speed remaining the same, or to increase the speed of the ship with the same consumption of fuel; this, taking into consideration the power absorbed by the necessary air compressors.

The attached drawing shows, as an example, in a diagrammatic way how the present process can be applied in practice.

Fig. 1 is a side view of a ship.

Fig. 2 is a horizontal section.

The front part of the hull is lined inside by a second wall 2 which forms together with the outer shell a narrow chamber which is connected by a system of pipes to a blower (not shown) which is fed by any kind of

compressor. The outer wall is perforated by a great number of little holes 3 spread over the whole immersed surface of the hull, and over a length, which can be, for example, equal to one tenth of the length of the vessel, 55 there being, for instance 250 holes per square meter.

These holes can have a diameter of 4 millimeters in the upper parts, and 6 millimeters in the lower parts. 60

When the ship moves, air will be compressed in the chamber 1/2 at a pressure slightly in excess of the water pressure at the level of the keel, so much so that a great number of bubbles will escape from all the 65 perforations in the ship's side.

These bubbles will rise along the hull and form against its walls an emulsion layer which will extend aft to a greater or lesser extent according to the speed of the ship, for 70 instance covering the trapezoidal surface *a b c d*. If one wishes to cover a greater surface of the sides of the ship, the chamber 1/2 can be extended backwards, especially in its lower parts, or one can arrange perforations 75 along the keel, for instance, in order to inject compressed air at all suitable spots.

If necessary, one can also subdivide the chamber 1/2 by longitudinal partitions, and supply the superposed compartments thus 80 formed with air at a pressure corresponding to the depth of each below the water line.

In applying the present procedure to a ship already built, the actual hull would be used for the inner wall of the air chamber, 85 and one would fix onto the outside of the hull a perforated wall kept at a slight distance from the former by suitable means.

The invention is, of course, not limited to this practical form, and the means of injecting compressed air into the water along the hull can be arranged in another form, perforated tubes, flat nozzles, etc.

One could also use in the place of air such gaseous fluids as may be available on board. 95

I claim:

In a ship, means for reducing the resistance offered to its advance by the friction of the water comprising double walls disposed at the front part of the ship so as to form a 100

chamber for the reception of compressed gaseous fluid, means for introducing such fluid into said chamber, and a plurality of apertures formed in the outer wall of said chamber for permitting the escape of the compressed fluid, the cross-sectional area of which apertures increases with their depth of immersion in the water as and for the purpose described.

10 In testimony whereof I have signed my name to this specification.

GEORGES MARCONNET.
